WIRE-DRAWING MACHINE

John H. Hitchcock, Worcester, and Edmund S. Murrah, Shrewsbury, Mass., assignors to Morgan Construction Company, Worcester, Mass., a corporation of Massachusetts

Application July 30, 1948, Serial No. 41,524

5 Claims. (Cl. 205—14)

This invention relates to wire-drawing machines, and more particularly to machines of the type having a series of dies through which the wire is drawn by means of rotating blocks or drums to effect successive reductions of the wire.

It has been recognized heretofore that certain important advantages would be obtained by maintaining an appreciable tension in the wire between each block and the succeeding die. Such so-called "back pull" will in general improve the quality of the wire, prolong the life of the dies by reducing the die friction and the resultant heat, and in many cases permit the drawing of the wire at higher speeds. There will often be a saving in power consumption. When back pull is applied to the wire approaching a particular die, there will necessarily be an increase in the "forward pull" in the wire leaving the die, but this increase in the forward pull will be less than the amount of the back pull. To obtain the maximum benefits from this type of wire-drawing, it is important to employ the highest practical back pull, the theoretical limit being that at which the resultant increased forward pull approaches the breaking strength of the wire. Many prior attempts have been made to draw wire in this manner, but with very little success. The principal difficulty encountered has been frequent breakage of the wire, and because of this it has heretofore been found necessary to employ comparatively low back pulls, resulting in very little benefit.

It is accordingly one object of the invention to provide a wire-drawing machine capable of operating in a thoroughly dependable manner with comparatively high back pull on the wire.

It is a further object of the invention to provide a multi-block machine for drawing wire through a series of dies and capable of operating satisfactorily with a comparatively high back pull between each block and the succeeding die without trouble from wire breakage.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is a top plan view of a multi-block wire-drawing machine, partially broken away;

Fig. 2 is a front elevation of the machine, partially broken away;

Fig. 3 is a graph showing the variation in the torques applied to the several blocks under different phases of the operation;

Fig. 4 is a somewhat diagrammatic view, largely in section, of certain valve mechanisms used for controlling the torque applied to the blocks;

Fig. 5 is a wiring diagram for the electrical apparatus used in connection with the machine;

Fig. 6 is a view similar to Fig. 1, but showing a modification of the invention;

Fig. 7 is a front elevation of the machine shown in Fig. 6, partially broken away;

Fig. 8 is an enlarged fragmentary view in section on the line 8—8 of Fig. 7; and

Fig. 9 is a wiring diagram for the electrical apparatus used in connection with the machine shown in Figs. 6 to 8.

The embodiment illustrated in Figs. 1 and 2 comprises

2

a horizontally elongated hollow frame or casing 20 which serves to support a series of five rotatable blocks 21 and a rotatable finishing block 22, the latter having the usual stripper 23 thereon to support a bundle of finished wire and to facilitate its removal from the block. A suitable wire-drawing die 24 is mounted in advance of each block. To facilitate subsequent discussion of the machine, Fig. 1 has been marked with braces and the numerals from 1 to 6 inclusive to indicate the relative order of the six wire reduction stages, each of which includes one die and one block. For example, we will later have occasion to mention the No. 1 die, or the No. 3 block, etc. The several blocks are all located on the top of the casing 20 and they are all rotatable about vertical axes.

In order to drive the blocks there is provided an electric motor 26 which is located at one end of the casing 20 and connected to a horizontal rotatable shaft 27, preferably made in several sections coupled to one another. This shaft carries a separate worm 28 (Fig. 1) for each of the blocks, each worm engaging a worm wheel 29 beneath each block. The worm wheel for the finishing block 22 is secured directly to the vertical spindle 31 of the said block so that it may be driven at a predetermined speed. The worm wheel for each of the blocks 21 is connected to the housing of a positive displacement rotary pump 32, as shown for example in the prior United States patent to Morgan et al. No. 2,185,416 granted January 2, 1940. As disclosed in said patent, each pump includes a rotor which is connected to the spindle of the associated block 21. The casing 20 provides a reservoir for oil, and the construction is such that each pump will draw a stream of oil from the reservoir and discharge it at a controlled pressure, thereby imposing a controlled torque on the pump rotor and on the block connected thereto. Each pump forms a hydraulic slip clutch which transmits torque to the corresponding block. The ratios of the several sets of worms and worm gears are such as to drive the pump housings at speeds somewhat higher than are required for the corresponding blocks, having in mind the particular wire drafting schedules to be performed by the machine. For purposes of control, as will be herein-after explained, a small pilot generator 33 (Fig. 1) is directly connected to the motor 26 and driven thereby.

When a machine of this type is to be placed in operation, it must first be threaded with wire. This involves pointing the wire, inserting the point through the No. 1 die, attaching the pointed wire to the No. 1 block by means of the usual grip while the driving motor 26 is stopped, driving the machine slowly until several wraps of wire are formed on the No. 1 block, and repeating this procedure for each of the remaining dies and blocks. When threading is completed, the machine must be accelerated to normal speed. After sufficient wire has accumulated on the finishing block 22, the machine must be stopped and a bundle of wire removed, whereupon the machine must again be accelerated to normal speed. In a machine operating with back pull, the various tensions throughout the entire machine are inter-related. It is our belief that the difficulties heretofore encountered by reason of wire breakage in back pull machines have been in very large part the result of failure to recognize the effect that the rotary inertia of the blocks has upon the wire tensions during rapid changes in speed. We propose to alter the driving torques applied to the respective blocks during acceleration or deceleration, with due regard to the rotary inertia of each block and to the speed of each block, in such a manner as to maintain the various wire tensions within allowable limits at all times. In order to make this matter clear, the invention will be explained in connection with a typical wire-drawing schedule. For this purpose we have chosen a schedule for reducing steel rope wire of .80% to .90% carbon content from a diameter of .162 inch to a diameter of .063 inch in six drafts, the finishing speed being 1500 feet per minute. The back pulls set forth in the following Table A are those which experimental data indicate will result in forward pulls equal to 90% of the breaking strength of the wire, this being as high as we consider it practical to go, having due regard to possible variations in the physical properties of the wire and in the numerous other factors involved.

3
Table A

Stage No.	0	1	2	3	4	5	6
Wire diam., inches	.162	.139	.119	.101	.086	.074	.063
Block diam., inches		.16	.16	.16	.16	.16	.22
Block R. P. M.	73.5	100.4	139	192.2	259.5	357.5	
Tensile strength of wire, 1,000 lbs./in. ²	175	219.5	253.5	279	297	310	319
Breaking strength of wire, lbs.		3,330	2,810	2,240	1,723	1,333	995
Forward pull without back pull, lbs.		1,725	1,611	1,365	1,081	822	645
Forward pull with back pull, lbs.		1,725	2,530	2,020	1,552	1,200	895
Back pull, lbs.		0	1,530	1,110	800	619	424
Die reaction with back pull, lbs.		1,725	1,000	910	752	581	471
Tangential force on block, lbs.		195	1,420	1,220	933	776	895
Rotary inertia of block, lbs. ft. ²		108.6	108.6	108.6	106.1	106.1	151.6 (600)

In the above table the die reaction with back pull is the difference between the forward pull and the back pull, and it is a measure of the amount of friction and wear on the die. As indicated in the table, this die reaction is in all cases, except for the No. 1 die (which operates without back pull), very much less than the forward pull without back pull. It will also be noted that the tangential force on the block is appreciably less than the forward pull without back pull in all cases except No. 6 block, which has no back pull to help it rotate. The two values for the rotary inertia of No. 6 block correspond respectively to the bare block and to the block loaded with a 500 pound bundle of finished wire. From the tangential forces on the blocks, as set forth above, the torques which must be employed to drive the blocks in normal back pull drawing can be readily computed. For successful operation of the machine, however, it is necessary to alter the applied torques in accordance with the particular conditions existing at any given time. Thus in the first stage of threading a die, the corresponding block must receive sufficient torque to pull the wire through without having to overcome back pull, and in the second stage of threading (when the slack in the wire ahead of the die has been taken up) additional torque will be required to overcome the back pull. When the machine is accelerated or decelerated, it is of the greatest importance that the driving torque at each block be properly controlled with due regard to its rotary inertia and its normal speed in order to maintain the various wire tensions within allowable limits.

The following Table B has been prepared to show the values of the driving torques in foot pounds which are required for the several blocks under certain different phases of the operation, in order to maintain the same wire tensions as those prevailing during normal wire drawing.

Table B

Block No.	1	2	3	4	5	6
Threading (1st stage)	1,150	1,075	910	721	549	590
Threading (2nd stage)		1,688	1,347	1,037	800	820
Drawing	980	946	814	621	519	820
Acceleration (6 seconds)	984	952	822	632	534	850
Stop (2 seconds)	968	928	790	588	474	732 (472)

It will be seen from the table that appreciable changes in torque are required for each block as the operation goes from one phase to another, and certain of these changes are very important for successful operation. For example, unless the required increased driving torque is applied to the blocks during acceleration, to overcome the rotary inertia of the blocks, the wire tensions throughout the machine will be increased, since the wire will compel all the blocks to accelerate simultaneously. However the forward pulls on all the dies (except No. 1) have already been established at 90% of the theoretical breaking strength of the wire, the 10% difference being considered the very minimum which can be tolerated if the operation is to be successful from a practical standpoint. Accordingly it will be apparent that any increase in the tension during acceleration will inevitably result in trouble from breakage of the wire. However, decreases in tension during acceleration, so long as at least some back pull is

maintained, can do no harm except for a loss of the full advantages of back pull during the few seconds required to bring the machine up to speed. Hence for the sake of dependability in operation we prefer to increase the torque applied to each block during acceleration to a value appreciably in excess of that set forth in the table as theoretically required to maintain the specified back pull but nevertheless below the value required to draw wire without the assistance of any back pull. The amount of increase above the theoretical requirements is not critical.

During stopping of the machine, the torque applied to each block should be decreased, and for simplicity of control we prefer to decrease the torque applied to each block during stopping by the same amount as the torque is increased during acceleration. By reasonable care in the selection of the amount of torque to be added and subtracted, the back pull at each die may be maintained somewhat lower, during both acceleration and stopping, than during normal drawing. The following Table C shows the particular torque changes which we propose to make for accelerating and stopping the machine in connection with the wire schedule under consideration, together with the resultant wire tensions throughout the machine. It will be noted that in all cases these tensions are below those encountered in normal drawing, and yet no slack can be produced, since an appreciable back pull is always maintained. The figures are based upon 6 seconds for acceleration and 2 seconds for stopping. The relatively short stopping time is considered desirable for reasons of safety, since any stop may be an emergency stop made necessary by some person becoming caught in the machine.

Table C

Stage No.	1	2	3	4	5	6
Acceleration (6 seconds):						
Theoretical torque to be added	4	6	8	11	15	
Actual torque to be added	45	50	60	50	30	---
Drawing torque	980	946	814	621	519	---
Total torque	1,025	996	874	671	549	---
Effective torque	1,021	990	866	660	534	---
Tangential force on block	1,531	1,485	1,299	990	801	735
Forward pull	1,725	1,727	1,508	1,203	952	735
Back pull	0	194	242	209	213	151
Die reaction	1,725	1,533	1,266	994	739	584
Stop (2 seconds):						
Theoretical torque to be subtracted	12	18	24	33	45	---
Actual torque to be subtracted	45	50	60	50	30	---
Total torque	935	896	754	571	489	---
Effective torque	947	914	778	604	534	---
Tangential force on block	1,420	1,371	1,167	906	801	716
Forward pull	1,725	1,794	1,615	1,345	1,090	816
Back pull	0	305	423	448	439	289
Die reaction	1,725	1,489	1,192	897	651	527

In Fig. 4 there is shown certain valve mechanism which serves to regulate the pressure of the oil discharged by one of the pumps 32 (say the No. 1 pump) and thereby control the torque applied to the corresponding block. It will be understood that a similar mechanism will be provided for each of the pumps. In the embodiment illustrated a pipe 35 leads from the discharge port of the pump (not shown) to a chamber 36 in the lower portion of a pressure regulating valve 37. An outlet port 39 leads downwardly from this chamber 36 to a pipe 40 through which the oil may return to the reservoir in the casing 20 (Fig. 1). A gauge 41 is connected by a pipe 42 to the chamber 36 to indicate the pressure therein, this being a measure of the torque applied to the corresponding wire-drawing block. The flow through the outlet port 39 is controlled by a valve member 44 which is supported by a piston 45 thereabove, this piston being vertically slidible within a cylindrical bore 46 above and in communication with the chamber 36. A piston rod 48 extends upwardly from the piston 45, and the lower portion of this rod is surrounded by a light coiled compression spring 49 which urges the piston downwardly. An orifice 50 is provided through the piston 45 so that a small stream of oil may flow upwardly therethrough from the chamber 36 to the interior of the bore 46 above the piston.

Oil from the interior of the bore 46 above the piston 45 is led through a pipe 52 to a manually adjustable pressure relief valve 53. This valve is provided with an inlet port 54 controlled by a spherical valve member 55,

and an outlet port 57 from which a pipe 58 may lead the oil back to the reservoir. The valve member 55 is urged toward its closed position by a coiled compression spring 59, and the force of this spring may be varied by a manually adjustable screw 60.

In the operation of the apparatus shown in Fig. 4, as so far described, oil discharged by the associated pump will flow through the pipe 35 to the chamber 36, and thence through the outlet port 39 and pipe 40 back to the reservoir. The pressure within the chamber 36, acting upon the lower surface of the piston 45, will hold the valve member 44 slightly above its seat to permit such flow. A relatively small continuous stream of oil will flow upwardly through the orifice 50 into the upper portion of the bore 46 and thence through the pipe 52 and the relief valve 53. For a given setting of the adjusting screw 60 of the relief valve, the pressure within the chamber 36 will remain substantially constant despite variations in the rate of flow through the pipe 35. This result will be brought about by vertical movements of the piston 45 and the valve member 44 under the influence of the slightest variations in the pressure within the chamber, this pressure being opposed by the force of the spring 49 and by the pressure of the oil within the upper portion of the bore 46. If the pressure within the chamber 36 increases ever so slightly, the valve member 44 will be moved upwardly to relieve the excess pressure by permitting increased flow through the outlet port 39. Similarly, the slightest decrease in pressure will cause downward movement of the valve member 44 to restore the desired pressure by decreasing the flow through the outlet port 39. By adjustment of the relief valve screw 60, the oil pressure above the piston 45 can be changed, and this will cause the oil pressure in the chamber 36 to change as required to maintain the piston in a balanced or floating condition.

The relief valve 53 for each wire-drawing stage is adjusted so that the correct pressure will be maintained in the corresponding chamber 36 to provide the desired driving torque for the corresponding block during normal drawing of the wire. This adjustment will ordinarily not be changed unless the machine is to be used for a different wire-drawing schedule. However, as explained above, we propose to make temporary changes in the driving torque when the machine is to be threaded, accelerated, or stopped. For this purpose we provide certain additional apparatus, which will now be described.

As shown in Fig. 4, the piston rod 48 carries a second piston 62 which slides within a cylindrical bore 63 in the upper portion of the valve 37, this bore being closed at its upper end by a plug 64 having a recess 65 therein to receive the upper end of the piston rod. A pipe 66 is connected to the recess 65 to lead oil therefrom back to the reservoir. By applying oil at suitable pressures to the upper or lower surfaces of the piston 62 during certain phases of the wire-drawing operation, the oil pressure within the chamber 36 may be changed to vary the torque applied to the corresponding block in a desired manner. For this purpose we provide a pressure reducing and regulating valve 68, a four-way valve 69, and a three-way valve 70.

The valve 68 is of a well-known type having a valve member controlled by a spring-loaded diaphragm, the latter being subjected to the fluid pressure at the discharge side of the valve. Such valves are adapted to maintain a substantially constant predetermined discharge pressure despite wide variations in the inlet pressure. One suitable construction is disclosed in the United States patent to Temple No. Re. 19,545.

The four-way valve 69 is of the solenoid-actuated spring-centered type. This valve is provided with a cylindrical bore 72, an inlet port 73 at the central portion of the bore, two exhaust ports 74 and 75 adjacent the respective ends of the bore, and two ports 77 and 78 communicating with the bore at points intermediate the inlet port 73 and the respective exhaust ports 74 and 75. Pipes 79 may lead from the exhaust ports to the oil reservoir. A spool shaped valve member 81 is slideable within the bore 72 and is normally held in its central position, as shown, by two opposed coiled compression springs 82 located within the end portions of the bore. With the valve member in this position, any oil entering the inlet port 73 will be trapped within the valve spool, and both the ports 77 and 78 will be connected through the bore 72 to the exhaust. Two solenoids AS1 and DS1 are

connected to the opposite ends of the valve member 81. These parts are so arranged that if the solenoid AS1 is energized, the valve member will be moved to connect the inlet port 73 to the port 77, while the port 78 remains connected to exhaust. If on the other hand the solenoid DS1 is energized, the valve member will be moved in the opposite direction to connect the inlet port 73 to the port 78, while the port 77 is connected to exhaust.

The three-way valve 70 is of the solenoid-actuated spring-return type. This valve is provided with a cylindrical bore 84, an inlet port 85, and two control ports 86 and 87. The end portions of the bore are connected to pipes 90 which may lead to the oil reservoir. A spool shaped valve member 91 is slideable within the bore 84 and is normally held at the left end thereof, as shown, by a coiled compression spring 92. With the valve member in this position, the inlet port 85 will be closed, and the port 86 will be connected through the bore 84 to the port 87. A solenoid JS1 is connected to the right end of the valve member 91, and when this solenoid is energized it will move the valve member to the right so that the inlet port 85 will be connected through the bore 84 to the port 87.

These various valves are connected to one another by piping as follows. A pipe 94 leads from the pump discharge pipe 35 to the inlet of the pressure reducing valve 68, and a pipe 95 leads from the outlet of the valve 68 to the inlet port 73 of the valve 69. A pressure gauge 96 is connected to the pipe 95. A pipe 98 leads from the pipe 94 to the inlet port 85 of the valve 70. The port 77 of the valve 69 is connected to the port 86 of the valve 70 by a pipe 99. The port 87 of the valve 70 is connected to the upper portion of the bore 63 by a pipe 100. The port 78 of the valve 69 is connected to the lower portion of the bore 63 by a pipe 101.

These various parts are so constructed and arranged that when the No. 1 block is to be jogged during the threading of the No. 1 die, and the solenoid JS1 is energized, oil from the pipe 35 may flow through the pipe 98, the port 85, the bore 84, the port 92 and the pipe 100 to the upper end of the bore 63. This will urge the pistons 62 and 45 downwardly, closing the valve member 44, and increasing the pump discharge pressure in the pipe 35 so that the pump may transmit ample torque for threading purposes. When the block is to be accelerated, with the solenoid JS1 de-energized and the solenoid AS1 energized, the reduced pressure within the pipe 95 will be transmitted through the port 73, the bore 72, the port 77, the pipe 99, the port 86, the bore 84, the port 87, and the pipe 100 to the upper end of the bore 63. This will urge the piston 62 downwardly and increase the pressure within the pipe 35 required to maintain flow through the port 39, thereby increasing the torque which the pump will normally transmit by an amount determined by the adjustment of the pressure reducing valve 68. When the block is to be decelerated to stop the machine, the solenoid DS1 will be energized so that the reduced pressure within the pipe 95 will be transmitted through the port 73, the bore 72, the port 78, and the pipe 101 to the lower end of the bore 48. This will urge the piston 62 upwardly and decrease the pressure within the pipe 35 required to maintain flow through the port 39. This will decrease the torque which the pump will normally transmit by an amount determined by the adjustment of the pressure reducing valve 68. Since the effective areas of the upper and lower surfaces of the piston 62 are equal, the torque added for acceleration will be equal to the torque subtracted for deceleration. During normal running at a substantially constant speed, with the three solenoids de-energized, both ends of the bore 63 will be connected to the exhaust pipes 79 through the intervening pipes and valves. Under these conditions the torque transmitted by the pump will be controlled by the adjustment of the relief valve 53.

It will be understood that a pressure control apparatus as shown in Fig. 4 will be required for each of the pumps 32. For the purpose of description, the five jogging solenoids will be designated JS1 to JS5 inclusive. Similarly the five accelerating solenoids will be designated AS1 to AS5 inclusive, and the five decelerating solenoids will be designated DS1 to DS5 inclusive. These various solenoids all appear in the wiring diagram of Fig. 5, which will now be described.

In Fig. 5 there is illustrated diagrammatically certain electrical apparatus whereby the machine may be oper-

ated in a desired manner. This includes a source 103 of constant voltage direct current controlled by a main switch 104. The motor 26 is provided with a commutating field 105 and a main field 106. The pilot generator 33 is provided with a field 107. Two rheostats 109 and 110 are provided, these being mechanically connected for simultaneous adjustment. A line contactor A includes a normally open switch A1 and a normally closed switch A2. A run contactor B includes normally open switches B1, B2, B3, B4, and B5, and normally closed switches B6 and B7. A dynamic brake contactor C includes a normally open switch C1. An accelerating contactor D includes a normally open switch D1 and a normally closed switch D2, while a second accelerating contactor E includes a normally open switch E1 and a normally closed switch E2. A decelerating contactor F includes a normally open switch F1. A field accelerating relay G includes a normally open switch G1. A full field relay H of the time delay type (as indicated by the letters "t. d.") includes a normally open switch H1. An accelerating time delay relay J includes a normally closed switch J1, and a second accelerating time delay relay K includes a normally closed switch K1. A decelerating time delay relay L includes a normally open switch L1. An accelerating relay M includes a normally closed switch M1. A normally closed stop push button switch 112 is provided, and a normally open run push button switch 113. For jogging block No. 1, a pair of interconnected normally open push button switches 114 and 115 are provided. Similar pairs of switches 116 and 117 are provided for jogging No. 2 block, together with switches 118 and 119 for No. 3 block, switches 120 and 121 for No. 4 block, switches 122 and 123 for No. 5 block, and a single normally open switch 124 for No. 6 block. A resistance 125 is provided to aid in obtaining the desired control of the motor 26.

The electrical connections for the various switches and other devices as shown in Fig. 5 will now be described. The switch A1, the armature of the motor 26, the commutating field 105, the switches E1 and D1, and the field accelerating relay G are connected in series across the main switch 104. The switch C1 and a portion of the resistance 125 are connected in series across the armature 26 and the field 105. A second portion of the resistance 125 is connected across the switch E1, and a third portion is connected across the switch D1. The field 106 and the rheostat 109 are connected in series across the main switch 104. Each of the switches G1 and H1 is connected across the rheostat 109. The switches 112 and 113 and the run contactor B are connected in series across the main switch 104. The switch B1 is connected across the switch 113. The switch B2 and the line contactor A are connected in series across the main switch 104. Each of the switches 114, 116, 118, 120, 122 and 124 is connected across the switch B2. The switch B3, the accelerating contactor D, and the switch J1 are connected in series across the main switch 104. The accelerating contactor E and the switch K1 are connected in series across the contactor D. The following groups of devices are each connected in series across the main switch 104; the switch B6 and the accelerating relay J; the accelerating relay K and the switch D2; the full field relay H and the switch E2; the switch A2 and the dynamic brake contactor C; the switch 115 and the jog solenoid JS1; the switch 117 and the jog solenoid JS2; the switch 119 and the jog solenoid JS3; the switch 121 and the jog solenoid JS4; the switch 123 and the jog solenoid JS5; and the switch B4, the switch M1, and the accelerating solenoid AS1. Each of the remaining accelerating solenoids AS2 to AS5 inclusive is connected across the solenoid AS1. The armature of the pilot generator 33, the accelerating relay M, and the rheostat 110 are connected in an independent series circuit. The field 107 is connected across the main switch 104. The following additional groups of devices are each connected in series across the main switch 104: the switch B5 and the decelerating relay L; the switch B7, the switch L1, and the decelerating contactor F; and the switch F1 and the decelerating solenoid DS1, the remaining decelerating solenoids DS2 to DS5 inclusive being connected across the solenoid DS1.

The operation of the embodiment illustrated in Figs. 1 to 5 inclusive will now be apparent from the above disclosure. Assuming that the main switch 104 is closed, the contactor C and the relays H, J and K will be ener-

gized. Hence switches C1 and H1 will be closed, while switches J1 and K1 are open. To thread the No. 1 die, the No. 1 block may be jogged by pressing the No. 1 jog button to close the switches 114 and 115. Closing the switch 114 will energize the line contactor A, closing the switch A1 and opening the switch A2, de-energizing the dynamic brake contactor C, and opening the switch C1. As the switch A1 closes, the motor 26 will start and operate at slow speed, since the full field 106 is applied by the closed switch H1, and the portions of the resistance 125 controlled by the switches E1 and D1 are in series with the motor armature. The closed switch 115 will energize the solenoid JS1, so that the No. 1 pump will transmit the necessary torque to the No. 1 block for threading purposes. When the desired number of wraps of wire have been wound on the block, the jog button will be released, opening the switches 114 and 115. This will de-energize the line contactor A, open the switch A1, close the switch A2, energize the brake contactor C, close the switch C1, and cause the motor 26 to stop by dynamic braking by inserting a portion of the resistance 125 across the motor. The remaining blocks may be jogged successively in a similar manner by pressing the corresponding jog buttons, until the machine is fully threaded. Since the No. 6 block has no corresponding pump or jogging solenoid, its jog button includes only the single switch 124. It will be noted that while any of dies Nos. 2 to 6 are being threaded, the preceding blocks will need only normal running torque, for by the time the wire has tightened around these blocks sufficiently to give capstan effect thereto, the back tension will be available to assist in their rotation, as will be apparent from Fig. 3.

Upon completion of the threading, the machine will be ready to run, and the operator need merely press the run button to close the switch 113 momentarily, thus energizing the run contactor B, so that switches B1 to B5 inclusive will close, and switches B6 and B7 will open. The closed switch B1 will maintain energization of the contactor coil B. The closed switch B2 will energize the line contactor A to start the motor 26 at slow speed. The closed switch B4 will energize all the accelerating solenoids AS1 to AS5 inclusive, so that all of the pumps 32 will transmit the proper accelerating torques to their respective blocks to overcome the rotary inertia thereof. The amount of torque to be added to the normal running torque will be determined in each case by the adjustment of the corresponding pressure reducing and regulating valve 68 (Fig. 4). As the switch B6 opens it will de-energize the accelerating relay J, and as this relay times out the switch J1 will close, energizing the accelerating contactor D. The switch D1 will thereupon close, shunting the corresponding portion of the resistance 125, and increasing the motor speed. The switch D2 will open, deenergizing the accelerating relay K. As this relay times out the switch K1 will close, energizing the accelerating contactor E. The switch E1 will close, shunting the corresponding portion of the resistance 125, and the motor will accelerate to its basic speed. At the same time the switch E2 will open, de-energizing the full field relay H. As this relay times out, the switch H1 will open, rendering the rheostat 109 effective to reduce the strength of the motor field 106 and causing the motor to accelerate to its present speed as determined by the adjustment of the rheostat. During this phase of the operation the relay G will control the rate of acceleration. If this rate exceeds a predetermined value, the armature current will become sufficient to cause the relay to pick up, closing the switch G1, shunting the field rheostat 109, and increasing the strength of the field 106. This will reduce the armature current and cause the relay G to drop out. This relay will continue to pick up and drop out momentarily until the motor has reached its preset speed. At this time the pilot generator 33, which is driven by the motor 26, will reach sufficient speed to supply the voltage required to pick up the accelerating relay M, thus opening the switch M1 and de-energizing the accelerating solenoids AS1 to AS5 inclusive. This will cause the pumps 32 to transmit the normal running torques to their respective blocks as determined by the adjustments of the corresponding pressure relief valves 53 (Fig. 4). Thus the machine will continue to operate with predetermined back-tensions throughout.

When a sufficient quantity of wire has accumulated on

the finishing block 22, the operator will stop the machine and remove a bundle of wire. The machine may be stopped by merely pressing the stop button to open the switch 112 momentarily. This will de-energize the run contactor B, opening the switches B1 to B5 inclusive, and closing the switches B6 and B7. As the switch B2 opens, it will de-energize the line contactor A, the switch A1 will open, and the switch A2 will close, energizing the brake contactor C and closing the switch C1. This will cause the motor 26 to stop very quickly by dynamic braking. As the switch B7 closes it will energize the decelerating contactor F and close the switch F1, thereby energizing all of the decelerating solenoids DS1 to DS5 inclusive. This will reduce the torque applied by the several pumps 32 to the respective blocks and cause all of the blocks to decelerate in step with the motor 26. As the switch B5 opens, it will de-energize the decelerating relay L, and this relay will time out shortly after the machine has come to a stop. The switch L1 will then open, de-energizing the decelerating contactor F, opening the switch F1, and de-energizing the decelerating solenoids DS1 to DS5.

There are important advantages in positively gearing the No. 6 block (rather than one of the preceding blocks) to the motor 26. If the positive drive were applied to one of the first five blocks, it would be necessary to apply a controlled torque to the No. 6 block, and to vary this torque (during acceleration and deceleration) in accordance with changes in the rotary inertia of the block, which varies widely in accordance with the amount of finished wire accumulated on the block. Furthermore, in starting the machine, the positively driven block would tend to start an instant ahead of the hydraulically driven blocks, and this might create sufficient slack in the wire leaving the positively driven block to cause a momentary loss of capstan effect on this block. As soon as the following blocks had taken up this slack, the capstan effect would be restored very suddenly, producing a heavy jerk on the wire immediately anterior to the positively driven block, with probable breakage of the wire. A further advantage of our preferred construction is that the delivery speed of the finished wire is directly determined by the speed of the motor 26, which can be changed by adjustment of the field rheostat 109. Such adjustment effects a corresponding adjustment in the rheostat 110, so that the relay M will always pick up at the proper motor speed.

It will be apparent that the invention provides a thoroughly dependable multi-block wire-drawing machine which can be operated with a comparatively high back pull on the wire. The breakage of wire and the production of slack wire during acceleration or deceleration of the machine is substantially eliminated, and an accurate control of the wire tensions throughout the machine is obtained.

In Figs. 6 to 9 inclusive there is shown a modification of the invention, certain of the reference numerals of Fig. 1 being utilized when applicable. Thus there is provided the frame or casing 20, the five blocks 21, the finishing block 22 with its stripper 23, and the six dies 24. The machine is driven by the electric motor 26, to which the small pilot generator 33 is directly connected.

In this embodiment each of the six blocks is mounted on the upper end of a vertical rotatable spindle 130 to which a worm gear 131 is fixed. The gear 131 for each of the first five blocks 21 meshes with a separate horizontal worm 132, while the gear 131 for the finishing block 22 meshes with a horizontal worm 133. The motor 26 drives a horizontal shaft 135 which is supported in suitable bearings 136. This shaft is preferably made in several sections coupled to one another. The worm 133 for the finishing block 22 is secured directly to the shaft 135 to provide a positive drive for this block. Each of the worms 132 for the blocks 21, however, is of hollow construction, as shown in Fig. 8, so that the shaft 135 may pass axially therethrough, these worms being rotatably mounted in suitable bearings 137.

Means is provided to transmit a predetermined controlled torque from the shaft 135 to each of the worms 132. For this purpose each worm 132 is connected at one end to the driven member 139 of a suitable magnetic slip clutch 140 (Fig. 8), which may be of the well-known eddy current type. Each of these five clutches includes a driving member 141 fixed to the shaft 135 and carrying an energizing coil, these coils being identified as

EC1 to EC5 inclusive to correspond with the respective blocks. Electric current is transmitted to each coil in known manner through a pair of brushes 143 which engage a pair of slip rings 144 carried by the shaft 135, the ends of the coil being connected to the slip rings. The rings are of course insulated from the shaft and from one another. The torque transmitted by each clutch 140 will depend upon the extent to which its coil is energized, and the speed ratios of the several sets of worm gears will be such that each of the worms 132 will rotate at a somewhat lower speed than the shaft 135 when carrying out the particular wire drafting schedules for which the machine is adapted. Thus in normal continuous wire drawing there will be some slippage in each clutch.

In Fig. 9 the control mechanism for the motor 26 and for the several magnetic clutches is shown diagrammatically. Many parts of this mechanism are the same as in Fig. 5, and the same reference symbols have been employed wherever applicable. Thus there is an electric power source 103 and a main switch 104. The motor 26 has a commutating field 105 and a main field 106. The pilot generator 33 has a field 107. Two mechanically connected rheostats 109 and 110 are provided. There is a stop push button 112 and a run push button 113. Push button switches 114 to 124 are provided for jogging purposes. There is provided a line contactor A, a run contactor B (from which the switch B7 of Fig. 5 has been omitted), a dynamic brake contactor C, two accelerating contactors D and E, and a motor control resistance 125. Further provided is a field accelerating relay G, a full field relay H, two accelerating time delay relays J and K, and an accelerating relay M. There is also provided further apparatus (not required in Fig. 5) including two torque increasing relays N and O, two torque decreasing relays P and Q, five torque control rheostats RH1 to RH5 inclusive, and five torque control resistances RE1 to RE5 inclusive. The relay N includes six normally open switches N1 to N6 inclusive, the relay O includes five normally open switches O1 to O5 inclusive, the relay P includes six normally open switches P1 to P6 inclusive, and the relay Q includes five normally open switches Q1 to Q5 inclusive. Each of the relays C and Q is of the time delay type, as indicated by the letters "td" adjacent thereto.

The electrical connections between the various parts in the upper portion of Fig. 9 are similar to the corresponding connections in Fig. 5, and it is considered unnecessary to repeat the description here. This applies to the connections for the motor 26, the pilot generator 33, the stop button 112, the run button 113, the rheostats 109 and 110, the contactors A, B (except switches B4 and B5), C, D, and E, and the relays G, H, J and K. In addition, the following series circuits are provided across the main switch 104: the switch B4, the switch M1, and the relay N; the switch N6 and the relay O; the switch B5 and the relay P; the switch P6 and the relay Q; the rheostat RH1, the resistance RE1, and the clutch coil EC1; the rheostat RH2, the resistance RE2, and the clutch coil EC2; the rheostat RH3, the resistance RE3, and the clutch coil EC3; the rheostat RH4, the resistance RE4, and the clutch coil EC4; and the rheostat RH5, the resistance RE5, and the clutch coil EC5. The push button switches 114, 116, 118, 120, and 122 are connected across the resistances RE1, RE2, RE3, RE4, and RE5 respectively. Each of the push button switches 115, 117, 119, 121, 123, and 124 is connected across the switch B2. Each of the switches N1, O1, P1 and Q1 is connected across a different portion of the resistance RE1, leaving a fifth portion thereof unshunted. The other resistances RE2 to RE5 inclusive are similarly controlled by the correspondingly numbered switches of the relays N, O, P and Q.

In the operation of the embodiment shown in Figs. 6 to 9 inclusive, with the main switch 104 closed, the No. 1 block may be jogged for threading purposes by pressing the No. 1 jog button to close the switches 114 and 115. The closed switch 115 will energize the line contactor A and cause the motor 26 to run at a slow speed, as already described in connection with the previous embodiment. The closed switch 114 will short out the entire resistance RE1 and provide sufficient energization to the clutch coil EC1 to afford the transmission of ample torque to the No. 1 block for threading purposes. The remaining blocks may be jogged in a similar manner until the machine has been completely threaded. The run

button 113 will then be pressed, energizing the run contactor B and causing the motor 26 to accelerate in the same manner as in the previous embodiment. The closed switch B4 will energize the relay N, and the closed switch B5 will energize the relay P. As the switch N6 closes it will energize the relay O, and as the switch P6 closes it will energize the relay Q. Thus all the switches for the relays N, O, P and Q will be closed, and the corresponding portions of the resistances RE1 to RE5 inclusive will be shunted. With the various resistances properly adjusted this will provide the correct energization for the several clutch coils to give the proper torque for acceleration of the corresponding blocks. As the motor 26 and the pilot generator 33 reach normal running speed, the relay M will pick up, opening its switch M1 and breaking the circuit to the relay N. As this relay drops out, all the N switches will open, and the circuit to the relay O will be broken. As this relay times out, all the O switches will open. Thus additional portions of the resistances RE1 to RE5 will be rendered effective in two successive steps to reduce the excitation of the corresponding clutch coils and to reduce the torques at the corresponding blocks to the normal running values.

To stop the machine it is merely necessary to press the stop button 112. This will de-energize the run contactor B, which will immediately drop out. As the switch B2 opens, the line contactor A will be de-energized, and the motor 26 will stop quickly under the influence of dynamic braking, as described in connection with the previous embodiment. As the switch B5 opens, the relay P will drop out, opening all the P switches and rendering the corresponding portions of the RE resistances effective to reduce the energization of the EC coils. As the switch P6 opens it will de-energize the relay Q, and as this relay times out all the Q switches will open, rendering still further portions of the RE resistances effective to reduce the current flow through the EC coils. Thus with the various resistances properly adjusted, the torques applied by the clutches 140 to the blocks Nos. 1 to 5 will be decreased sufficiently to cause these blocks to decelerate in step with the motor 26 without creating slack or excessive tension in the wire at any point.

It will be apparent that the invention provides a new and highly advantageous construction for a multi-block wire-drawing machine. The wire tensions throughout the machine are held at desired values at all times, and the torque applied to the blocks during changes in speed is so altered as to minimize the danger of wire breakage. While two embodiments of the invention have been illustrated, other embodiments may occur to those skilled in the art in the light of our disclosure and within the scope of our claims.

Having thus described our invention, what we claim as new and desire to secure by Letters Patent is:

1. A driving and control apparatus for a continuous wire-drawing machine having a plurality of rotatable drums and having dies situated between said drums, said apparatus comprising a driven shaft adjacent each drum, a variable torque transmission connecting each drum except one to its driven shaft, a starter mechanism for initiating the motion of the machine, a stopping mechanism for initiating the stoppage of the machine, a first control device connected to each said transmission and maintaining a constant, predetermined torque transmittal to its respective drum during normal running operation of the machine, a second control device connected to each said transmission device and to said starter mechanism for causing the torque transmission to increase substantially upon actuation of said starter mechanism, a third control device connected to each said transmission device and to said stopping mechanism for causing the torque transmission thereof to decrease substantially upon actuation of said stopping mechanism, the said one drum being directly connected to its drive shaft to control the speed of the machine, the said increase and decrease in torque transmission being of values so related to the rotary inertia of the respective drum as to maintain wire tension below the breaking strength of the wire.

2. A driving and control apparatus for a continuous wire-drawing machine having a plurality of rotatable drums and having dies situated between said drums, said apparatus comprising a driven shaft adjacent each drum, a magnetic clutch having variable torque characteristics connecting each drum except one to its driven shaft, a starter mechanism for initiating the motion of the ma-

chine, a stopping mechanism for initiating the stoppage of the machine, a first control device connected to each clutch and maintaining a constant, pre-determined torque transmission to its respective drum during normal running operation of the machine, a second control device connected to each said clutch and to said starter mechanism for causing the torque transmission to increase substantially upon actuation of said starter mechanism, a third control device connected to each said clutch and to said stopping mechanism for causing the torque transmission thereof to decrease substantially upon actuation of said stopping mechanism, the said one drum being directly connected to its drive shaft to control the speed of the machine, the said increase and decrease in torque transmission being of values so related to the rotary inertia of the respective drum as to maintain wire tension below the breaking strength of the wire.

3. A driving and control apparatus for a continuous wire-drawing machine having a plurality of rotatable drums and having dies situated between said drums, said apparatus comprising a driven shaft adjacent each drum, a hydraulic clutch having variable torque transmission characteristics connecting each drum except one to its driven shaft, a starter mechanism for initiating the motion of the machine, a stopping mechanism for initiating the stoppage of the machine, a first control device connected to each said clutch and maintaining a constant, pre-determined torque transmittal to its respective drum during normal running operation of the machine, a second control device connected to each said clutch and to said starter mechanism for causing the torque transmission to increase substantially upon actuation of said starter mechanism, a third control device connected to each said clutch and to said stopping mechanism for causing the torque transmission thereof to decrease substantially upon actuation of said stopping mechanism, the said one drum being directly connected to its drive shaft to control the speed of the machine, the said increase and decrease in torque transmission being of values so related to the rotary inertia of the respective drum as to maintain wire tension below the breaking strength of the wire.

4. A driving and control apparatus for a continuous wire-drawing machine having a plurality of rotatable drums and having dies situated between said drums, said apparatus comprising a motor and a drive shaft driven by the motor, a magnetic clutch having variable torque characteristics connecting each drum except one to the drive shaft, a starter switch mechanism for initiating the motion of the machine by impressing current on said motor and impressing a separate pre-determined current on each clutch, a stopping switch mechanism for initiating the stoppage of the machine by removing the current from said motor, a first control device connected to each clutch and maintaining the said pre-determined current at a constant value during normal running operation of the machine, a second control device connected to each said clutch and to said starter mechanism for causing the current to the clutch to increase substantially upon actuation of said starter mechanism, a third control device connected to each said clutch and said stopping mechanism for causing the current in the clutch to decrease substantially upon actuation of said stopping mechanism, the said one drum being directly connected to the drive shaft to control the speed of the machine, the said increase and decrease in current causing a corresponding change in torque transmission by said clutch of values so related to the rotary inertia of the respective drum as to maintain wire tension below the breaking strength of the wire.

5. A driving and control apparatus for a continuous wire-drawing machine having a plurality of rotatable drums and having dies situated between said drums, said apparatus comprising a motor and a drive shaft driven by the motor, a hydraulic clutch having variable torque transmission characteristics connecting each drum except one to its driven shaft, a starter mechanism for initiating the motion of the machine by impressing current on the motor and impressing a separate pre-determined hydraulic pressure on each clutch, a stopping mechanism for initiating the stoppage of the machine by removing the current from said motor, a first control device connected to each clutch and maintaining the said pre-determined pressure at a constant value during normal running operation of the machine, a second control device connected to each said clutch and to said starter mechanism for causing the

pressure on the clutch to increase substantially upon actuation of said starter mechanism, a third control device connected to each said clutch and to said stopping mechanism for causing the pressure in the clutch to decrease substantially upon actuation of said stopping mechanism, the said one drum being directly connected to the drive shaft to control the speed of the machine, the said increase and decrease in pressure causing a corresponding change in torque transmission by said clutch of values so related to the rotary inertia of the respective drum as to maintain wire tension below the breaking strength of the wire.
